BAG FOR CHRISTMAS GIFTS

Robert Collins, Lakewood, N.J.

Application September 23, 1958, Serial No. 52,734

Term of patent 14 years

(Cl. D58—2)

FIG. 1.

FIG. 2.

Figure 1 is a front elevational view of a bag for Christmas gifts embodying my design.

Fig. 2 is a side elevational view as viewed from the left of Fig. 1.

The rear of the bag is plain. The drawing is lined to indicate contrasting colored areas.

I claim:

The ornamental design for a bag for Christmas gifts, as shown and described.
